UNITED STATES PATENT OFFICE

1,975,605

ELECTRIC CAR HEATER

William G. Hartwig, Chicago, Ill., assignor to
 Railway Utility Company, Chicago, Ill., a corporation of Illinois

Application March 7, 1932, Serial No. 597,101

3 Claims. (Cl. 219—34)

This invention relates to improvements in electric car heaters of the type which are supported or suspended beneath the seats in electric railway cars or in similar conveyances.

5 It is an object of the invention to disclose a construction which may be readily assembled, which will conform in use to the underwriters' requirements insofar as preventing excessive heating of the terminal connections and which 10 will direct the major portion of the heat downwardly against the floor of the car without undue heating of the seat above the heater unit.

It is a specific object of the invention to form 15 the casing of the heater unit with a reflector plate above the electrical resistance units and provide a partitioned heat insulated chamber above the reflector plate to prevent excessive heating of the top part of the heater.

Further improvements of the present invention 20 are directed to the construction of the terminal box which is supported by and insulated from an end wall of the main body of the heater casing and the design and support for the terminal extensions between the resistance units 25 and the terminal box which conduct the current to the heater units.

Additional improvements and features of novelty in the construction will be more readily apparent from the complete description taken in 30 connection with the attached drawings, in which

Figure 1 is a bottom view of the complete heater unit;

Figure 2 is a vertical longitudinal section;

Figure 3 is an end elevation, certain parts 35 being removed for clearness;

Figure 4 is a vertical transverse section taken on the plane indicated 4—4 in Figure 2;

Figure 5 is a detail section showing the terminal extensions, and

40 Figure 6 is a detail section taken on the plane indicated 6—6 in Figure 5.

The heater unit is adapted to be suspended beneath the seat of a street car in such relation that a number of such heaters will serve as a 45 means for keeping the car warm and the heat will be directed downwardly towards the floor of the car to cause more equal distribution of the heat throughout the car without communication to a disagreeable degree to the seat which 50 is above the heater. The end walls 10 and 12 are formed with outwardly directed flanges 14 and 16 at their upper portions which serve as the hangers for suspending the heater. A bottom wall 18 extending longitudinally between the 55 end walls 10 and 12 is formed arcuate in cross

section and provided with a plurality of openings 20 whereby the wall 18 is in the form of a grille. The reticulated bottom wall 18 is in engagement at its upper longitudinal edges with an arcuate copper reflecting plate 22, the concave surface of which faces downwardly as shown in Figure 4. Above the reflecting plate 22 there is arranged a cover casing 24 in the form of a closed chamber having an arcuate bottom wall 26 and a flat top wall 28 united at their longitudinal edges by the downwardly and inwardly inclined side walls 30. The space within the cover portion 24 is divided by a baffle plate 32 into a pair of side chambers 34—34 and a top chamber 36. The cover parts are attached to the end walls 10 and 12 which close the ends of the air chambers through screws 38 extending through the top wall 28, the spacing bushings 40, the baffle plate 32, the bottom wall 26 and the copper reflector 22 and finally into threaded engagement with brackets 42 fixed to the end walls 10 and 12.

Within the space between the arcuate grille 18 and the copper reflector 22 is mounted a pair of longitudinally extending resistance units 44 fastened at their ends to brackets 46 fixed to the end walls 10 and 12. As shown in Figure 6 each end of the resistance units is flattened as shown at 48 and spaced from the brackets 46 by an insulating bushing 50 which in turn receives an insulating bushing 52 passing through the flattened end 48 of the resistance unit and held by a shoulder 54. A screw bolt 56 extends through the bushing 52 and into threaded engagement with the bracket 46 for tightly clamping the resistance unit in place. A pair of terminals 58 are provided at one end of each of the resistance units 44. The terminals 58 include upwardly directed threaded studs 60 upon which are fastened nut members 62. The terminal extensions or lead-in strips 64 are formed channel-shaped in cross section having depending side flanges 66. The ends of the terminal extensions 64 which connect to the nut members 62 are securely fastened thereby by bending over the upper end of the nuts, as shown at 68. The terminal extensions 64 extend through the end wall 10 and are insulated therefrom by a bushing 70. The bushing 70 also serves as a spacing member between the end wall 10 and a radiating shield 72 which is adapted to direct the heat away from the contacts to the terminal extensions. Additional spacing bushings 74 may be provided, as shown in Figures 1 and 2.

The terminal extensions 64 are provided at 110

their ends with self-locking binding posts, generally designated 76. The details of the binding posts 76 are more fully described and the novel features claimed in my co-pending application, Serial No. 602,711 filed April 2, 1932. It is to be understood however that the tightening of the clamping screws 78 serves to fasten the ends of wires 80 to the terminal extensions 64 through clamping brackets 82.

10 A terminal box enclosing the wire connections to the terminal extensions is formed by an arcuate bottom wall 84, having louvers 86, clamped to a top plate 88 and closed at one end by a bracket 90 receiving the wires 80 or a wire conduit by opening 92. The terminal box is further protected by an insulating plate 71 spaced from the radiating shield 72. The terminal extensions are held against outward movement with respect to the bushing 70 by pins 94.

20 The heat radiated from the resistance unit 44 is reflected by the copper shield 22 in a downward direction and it is found that the copper shield prevents the absorption of too much heat by the partitioned air spaces 34 and 36. The majority of the heat is therefore directed downwardly through the grille 20 and against the floor of the car. The enclosure of the connections of wires 80 to the terminal extensions 64 is sufficiently heat-insulated from the main body of the heater to maintain a temperature not over 250° F. in accordance with the requirements of the underwriters.

I claim:

35 1. An electric car heater comprising a suspended casing composed of a pair of end walls, a grille-shaped bottom wall extending between and supported by said end walls, a reflector plate extending between said end walls above said bottom wall, a top casing part open at its ends 40 adapted to rest directly upon the top of said reflector in position between the end walls such

that the open ends of said top casing part are closed by said end walls, and an electric resistance heating unit extending between said grille-shaped bottom wall and said reflector supported by and insulated from the end walls of said casing. 80

2. An electric car heater comprising a pair of suspended end walls, a grille-shaped bottom wall longitudinally extending between said end walls, said bottom wall being arcuate in cross section, an electric resistance heating unit supported at its ends and insulated from said end walls, a reflector plate longitudinally extending from said end walls above said resistance unit, said reflector plate being arcuate in cross section and adapted to reflect the heat downwardly and a top member forming an insulating partition longitudinally extending between said end walls and including top and bottom walls and enclosing side walls, the bottom wall of said insulating partition being shaped to conform to the shape of said reflector plate, whereby said insulating partition rests upon and is supported by said reflector plate. 85 90

3. An electric car heater comprising a pair of end walls, a grille-shaped bottom wall extending longitudinally between said end walls, a plurality of electrical resistance heating units supported at their ends and insulated from said end walls above said grille-shaped bottom wall, a reflector plate longitudinally extending between said end walls, said reflector plate being arcuate in cross section with its concave side facing downwardly towards said resistance unit, means extending between said end walls immediately above said reflector plate forming a closed air chamber and a baffle plate extending longitudinally within said chamber to prevent undesirable heating of the top part of the heater unit. 100 105 110 115
